UNITED STATES PATENT OFFICE.

KARL RÖGER, OF BERLIN, GERMANY, ASSIGNOR TO MERGENTHALER LINOTYPE COMPANY, A CORPORATION OF NEW YORK.

TYPOGRAPHICAL MACHINE.

1,142,272.

Specification of Letters Patent. Patented June 8, 1915.

Application filed April 11, 1914. Serial No. 831,109.

To all whom it may concern:

Be it known that I, KARL RÖGER, a subject of the German Emperor, residing at 33 Tel-towerstrasse, Berlin, in the Empire of Germany, have invented new and useful Improvements in Typographical Machines, of which the following is a specification.

This invention consists of improved means for preventing matrices or type dies moving in the channels of their magazines while the latter are being changed.

In typographical machines, and particularly in matrix or type die composing and line casting machines, in which the magazines with their matrices are removed from the rear of the machine, a bar is pushed in at the upper end of the magazine before it is rocked rearward, or another locking device is provided to prevent the matrices from falling out. In magazine channels containing only a small number of matrices which does not completely fill those channels, the matrices which formerly were in the lower part of the magazine will slide into the upper part, striking against the locking device when the magazine is tilted, and vice versa when the magazine is put again into the machine they will strike against the escapement devices at the lower end. The matrices thereby become damaged, as they receive rather a sharp blow, and the invention has for its object to remedy this difficulty.

The drawing shows a constructional form of the invention when applied to a machine of the Mergenthaler system known under the trade mark "Linotype."

Figure 1 is a side elevation of the part of the machine in question and of the magazine. Fig. 2 is a part of Fig. 1 on an enlarged scale. Fig. 3 is a plan of a part of Fig. 1, Fig. 4 shows a somewhat altered constructional form of the invention. Figs. 5 and 6 are sectional views showing the magazine in different positions; and Fig. 7 is a detail view.

The magazine *a* with its supporting frame *b*, can be rocked to the rear about a pivot *c* in the machine frame *d*, so as to enable the magazine to be taken out of the machine rearwardly. Before the magazine is rocked down, its upper end is locked in the known manner, not shown in the drawing, in order to prevent the matrices from falling out. In order to prevent the matrices from shift-

ing to and fro in channels which are not quite full, further locking devices are provided, which, according to the drawing, consist for each channel of a two-armed lever *e*, which on its free end carries a locking pawl *f*, entering a hole in the bottom plate of the magazine, to lock the matrices. The locking pawl *f* is drawn out of the magazine by a spring *g*, which thus keeps it in an inoperative position. The movement of the pawl *f* into and out of the magazine, is effected by an eccentric or cam *h* engaging one arm of the lever *e*, and either rocking the latter in such a manner that the locking pawl *f* enters the magazine, or allowing the spring *g* to act upon it to withdraw the pawl from the magazine. The cam *h* is rotated by two arms *i*¹ and *i*², which are connected to its outer end and are adapted to coöperate with a fixed stud *k*¹ on the machine frame as the magazine is rocked downward and upward, the arrangement being such that during the downward movement of the magazine, the cam *h* will be turned to project the pawls *f* into the magazine channels, and during the upward movement of the magazine the cam will be rotated in the opposite direction to allow the pawls to be withdrawn from the magazine by the springs *g*. The operation is as follows: When the magazine is in its normal position as seen in Fig. 1, the arms *i*¹ and *i*² occupy the position shown in that figure. As the magazine is rocked downward for removal, the upper arm *i*¹ is brought into engagement with the stud *k*¹ on the framework, see Fig. 5, and the continued downward movement of the magazine causes the arm to be shifted clockwise to the position shown in Fig. 6, this shifting of the arm turning the cam *h* and effecting the projection of the pawls *f* into the magazine channels in the manner just described. When the new magazine has been substituted in the machine, the arms *i*¹ and *i*² occupy the position shown in Fig. 6, and when it is rocked upward to its normal position, the lower arm *i*² is brought into engagement with the stud *k*¹ and is thereby shifted counter-clockwise to the position shown in Fig. 5, this movement of the arm turning the cam *h* back to its original position so as to allow the springs *g* to withdraw the pawls from the magazine channels. It will be understood of course that this arrangement is merely shown by way of ex-

ample and in preferred form, but obviously other arrangements may be provided to secure the same results, the only requirement being that the locking of the matrices in the magazine be effected at some stage in the removal of the magazine, whether during the initial stage, as shown herein, or during a subsequent stage.

In the constructional form according to Figs. 4 and 7, a wedge member *m* is provided instead of the cam *h*, which member is tapered longitudinally and coöperates with an oppositely tapered wedge member *a*¹ on the under side of the magazine *a*, so that the longitudinal movement of the member *m* also causes its lateral or sidewise movement, which is imparted to the rocking levers *e*, and thus causes them to project the pawls *f* into the magazine channels or allows them under the action of the springs *g* to withdraw the pawls from the channels, according to the direction of movement of the wedge member. The movement of the wedge may be effected in any desired manner, but I prefer to employ the means shown in Fig. 7, wherein a curved plate *o* is fixed to the machine frame and is arranged in position to engage a notch *n* in one edge of the wedge, the effect being that as the magazine is swung upward and downward, the plate will engage in the notch and shift the wedge positively in opposite directions either to project the pawls *f* into the matrix channels or allow them to be withdrawn therefrom by the springs *g* according to the direction of movement of the magazine. In the drawing, only one locking device *e*, *f*, for each magazine channel is shown. Generally one device in the center of the magazine will be sufficient, but frequently two such locking devices may have to be arranged each at a distance of one-third of the length of the magazine from the top and bottom of the latter.

Having thus described my invention what I claim and desire to secure by Letters Patent of the United States is as follows:—

1. Means for preventing matrices or type dies moving in the channels of their magazines while the latter are being changed, comprising a locking device for each channel adapted to engage within it and means adapted to put the device into locking position as the magazine is moved from its working position in the machine and to put it out of that position as the magazine is moved into working position in the machine.

2. The combination with a channel of a magazine containing matrices or type dies and movable out of or into its machine, of a pawl adapted to engage within the channel and pivoted on a lever fulcrumed on the outside of the magazine, a spring urging the pawl out of locking position in the channel, and means adapted to put the pawl into

locking position as the magazine is moved from its working position in the machine and to allow the spring to put it out of locking position as the magazine is moved into working position in the machine.

3. The combination with a channel of a magazine, of a lever fulcrumed thereon, a pawl carried by one end of the lever and working through the respective side of the magazine, a spring for withdrawing the pawl from the channel, an eccentric on the magazine and engaging with the lever for projecting the pawl into the channel, two arms radiating from the eccentric in different directions, and a projection adapted by being supported independently of the magazine, to rock the arms and reverse the position of the pawl during the movement of the magazine from or to its working position in the machine.

4. In a typographical machine, the combination of a magazine having channels for the type or matrices and mounted to be swung downwardly from its operative position, and locking means arranged to engage within the channels between their ends to prevent the shifting of the type or matrices in the partially filled channels during the downward swinging of the magazine.

5. A magazine for typographical machines having a series of channels for the type or matrices and provided at one end with a series of escapements to control their release from the channels, the said magazine being also provided between its ends with locking means to engage within the channels and prevent the rearward shifting of the matrices in those partially filled.

6. A channeled magazine for typographical machines provided at one end with a series of escapements to control the release of the type or matrices therefrom, and also provided with a series of locking devices to engage within the channels and prevent the escape of the type or matrices from the opposite end.

7. A channeled magazine for typographical machines provided at one end with a series of escapements to control the release of type or matrices therefrom, and also provided substantially midway between its ends with a series of locking devices to engage within the channels and prevent the rearward shifting of the type or matrices therein.

8. In a typographical machine, the combination of a magazine to contain the type or matrices and mounted to be swung to and from its operative position, means for preventing the shifting of the matrices in the magazine, and automatic mechanism for rendering said means active and inactive as the magazine is moved from and to its operative position respectively.

9. In a typographical machine, the combi-

nation of a channeled magazine to contain the type or matrices and mounted to be swung to and from its operative position, a series of locking devices movable into and 5 out of the channels of the magazine for preventing the shifting of the type or matrices therein, and automatic mechanism for moving said locking devices into and out of the magazine as the latter is moved from and 10 to its operative position respectively.

10. In a typographical machine, the combination of a channeled magazine to contain the type or matrices, and mounted so as to be removable at will from its operative position in the machine, locking means to engage within the channels of the magazine between their ends and prevent the shifting of the type or matrices therein, and automatic mechanism for rendering said means 15 active during the removal of the magazine. 20

11. In a typographical machine, the combination of a channeled magazine to contain the type or matrices, and mounted so as to be removable at will from its operative position in the machine, locking means to engage within the channels of the magazine between their ends and prevent the shifting of the type or matrices therein, and automatic mechanism for rendering said means active and inactive as the magazine is removed from or replaced in its operative position in the machine. 25 30

In witness whereof I have hereunto set my hand in the presence of two witnesses.

KARL RÖGER.
